UNITED STATES PATENT OFFICE.

ISAAC EUSTER AND ROBERT EUSTER, OF MIDDLESBORO, KENTUCKY.

HAT PAD.

Application filed July 5, 1922. Serial No. 572,923.

To all whom it may concern:

Be it known that we, ISAAC EUSTER and ROBERT EUSTER, citizens of the United States, residing at Middlesboro, in the county of 5 Bell and State of Kentucky, have invented certain new and useful Improvements in Hat Pads, of which the following is a specification.

This invention relates to a fitting attachment for hats, and has for its object to provide an attachment of such class, in a manner as hereinafter set forth, for not only reducing the size of a hat when desired to fit the wearer, but furthermore providing 10 means for obtaining a comfortable fit of a hat when the head of the wearer is of irregular shape, more especially when the head is long instead of natural.

A further object of the invention is to 20 provide an attachment for the purpose referred to and in a manner as hereinafter set forth, to overcome the disadvantages of the ordinary cotton or paper stuffing employed for hat fitting purposes, such disadvantages being that the cotton stuffing rolls up and creates an ill fit, and that the paper filling causes the hat to feel very uncomfortable. This latter disadvantage is also present when the cotton stuffing rolls up.

30 Further objects of the invention are to provide a fitting attachment for hats, which is extremely simple in its construction and arrangement, strong, durable, readily applied to the hat, efficient in its use, and inexpensive to manufacture.

With the foregoing and other objects in view, the invention consists of the novel construction, combination and arrangement of parts, as hereinafter more specifically described and illustrated in the accompanying 40 drawings, wherein is shown an embodiment of the invention, but it is to be understood that changes, variations and modifications can be resorted to, which come within the 45 scope of the claims hereunto appended.

In the drawings wherein like reference characters denote corresponding parts throughout the several views:—

Figure 1 is a perspective view of the hat, 50 with the sweat band broken away, showing the adaption therewith of a hat fitting attachment in accordance with this invention,

Fig. 2 is a section of a hat illustrating the 55 position of the fitting attachment with respect to the sweat band of the hat,

Fig. 3 is a perspective view of a hat fitting attachment in accordance with this invention,

Fig. 4 is a front elevation, and

Fig. 5 is a vertical sectional view, broken away, of a modification.

Referring to the drawings in detail, 1 denotes the crown, 2 the rim and 3 the sweat band of a hat and the fitting attachment in 65 accordance with this invention is adapted to be interposed between the sweat band 3 and the inner face of the crown.

Referring to Figs. 1 to 4 of the drawings, the fitting attachment consists of an elongated body portion 4 of relatively thin flexible material, possessing a slight stiffening characteristic, and by way of example, a strip of thin transparent celluloid may be employed as the body portion for the attachment, but it is to be understood that any suitable material possessing the necessary flexibility and rigidity can be used. The longitudinal edge 5 of the body portion 4, is of greater length than the other longitudinal edge 6, and the said edges 5, 6, are connected together by the curved end edges 7.

Secured to one face of the body portion 4, is a cushioning element 8 of the same contour as the body portion 4, but the said cushioning element 8 is of less length and less width than the body portion 4, and when the cushioning element 8 is secured to the body portion 4, it is so positioned as to 80 provide the marginal portion of the body 4 to extend entirely around and project from the edges of the cushioning element 8. Means for securing the element 8 to the body 4 consist of a row of stitching 9, which extends throughout the marginal portion of 85 said element 8 and through the body portion 4.

The element 8 is formed from any suitable fabric which will set up a cushioning effect, 90 preferably, cotton padding of the desired thickness.

The pad is fitted between either a felt or straw crown and a leather or cloth sweat band and the pad when fitted lays uniform 105 either at the front, back or side of the sweat band. The cushioning element 8 is so set up with respect to the body portion to overcome any bulging of the sweat band at the top and bottom thereof and further in this 110 connection, it has been found that if the cushioning element is placed in position,

lower than what it is shown with respect to the body portion, it would cause the sweat band to bulge out and further cause the wearer to suffer from a pressing action and which would leave a crease mark on the wearer's forehead when the hat is removed.

Referring to Fig. 5 of the drawings, 10 indicates the body portion and 11 the cushioning element and both are of a contour corresponding to the body 4 and element 8, but in lieu of securing the element 11 to the body portion 10 through the medium of a row of stitching, the element 11 is secured to one face of the body portion 10 by a suitable adhesive material 12.

What we claim is:—

1. A fitting attachment for hats for interposition between the sweat band and the crown of the hat comprising a body portion formed of a narrow substantially thin strip of flexible material and a cushioning element secured to one face of said body portion, said cushioning element of less width and of less length than said body portion and positioned against the said face of said body portion to provide for the marginal part of the

body portion to extend entirely around and project from said element thereby preventing the bulging of the sweat band at the top and bottom thereof when the attachment is 30 mounted in fitting position.

2. A fitting attachment for hats for interposition between the sweat band and the crown of the hat comprising a body portion formed of a narrow substantially thin strip 35 of flexible material having each of its ends pointed, and a cushioning element of the same contour as the contour of said body portion and having its edges secured throughout to said body portion, said cushioning element of less length and of less width than the length and width of the body portion whereby the latter will project from each edge of said element thereby preventing the bulging of the sweat band at the top and bottom thereof when the attachment is 40 45 mounted in fitting position.

In testimony whereof, we affix our signatures hereto.

ISAAC EUSTER.
ROBERT EUSTER.
